PACKAGING PRESS

William L. Davis, Savannah, Ga., assignor to
 Union Bag & Paper Corporation, New York,
 N. Y., a corporation of New Jersey

Application December 17, 1949, Serial No. 133,615

4 Claims. (Cl. 226—14)

1

The present invention relates to improvements in packaging. More particularly it pertains to a bag press for compressing and packaging stacked paper bags in a wrapper or other suitable container.

A general object of the present invention is to provide a packaging machine which will receive and compress paper bags in stacked relation, insert the compressed stack into a wrapper, and deliver from the machine a neat and compact package.

More specifically it is an object of the present invention to provide a bag press having a receptacle for receiving paper bags in stacked relation, a press plate and means for compressing the stacked bags in the receptacle, said receptacle and press plate being constructed and adapted to receive a wrapper encircling said receptacle, plate and stacked compressed bags, a kicker plate and means for ejecting said bags and wrapper from the receptacle.

A further object of the invention is to provide a packaging machine which is simple to operate, sturdy and durable of construction and well suited to the purposes for which it is intended.

Other objects of the invention will in part be obvious and will in part appear hereinafter.

The invention accordingly comprises the features of construction, combination of elements and arrangement of parts which will be exemplified in the construction hereinafter set forth and the scope of the invention will be indicated in the claims.

For a fuller understanding of the nature and objects of the invention reference should be had to the following detailed description taken in connection with the accompanying drawings, in which:

Figure 1 is a side elevation of the bag press of the present invention;

Figure 2 is a corresponding front elevation with part of the front door broken away;

Figure 3 is an enlarged front view of the bag receptacle, partly in section, showing the kicker plate and trap door mechanism;

Figure 4 is a cross-sectional view on the line 4—4 of Figure 2 with the guide bar mount and guide bars omitted to show the kicker plate and bumper shafts fastened to such plate;

Figure 5 is a cross-sectional view on the line 5—5 of Figure 2;

Figure 6 is an enlarged front view of the bag receptacle, partly in section, showing the stacked bags under compression with a wrapper encircling the receptacle and press plate;

Figure 7 is a side view of the door lock and door trip arm;

Figure 8 is a cross-sectional view on the line 8—8 of Figure 4 showing the valve safety trip;

Figure 9 is a cross-sectional view on the line 9—9 of Figure 8.

Referring more particularly to the drawings, there is shown in Figure 1 a frame member 11

2

to which the various parts of the bag press are attached. This frame member may be secured to a suitable pedestal or stand to bring the press up to a height at which it will be convenient for the operator to insert bags. In addition, the bag press can be mounted at an angle so that the bag receptacle will be tilted toward the back and to the left to permit the bags to be stacked without falling from the receptacle.

Secured to the frame member 11 are right side plate 12, left side plate 13, and lower press plate 14 (see Figure 3), these plates constituting three sides of the lower portion of a bag receptacle. The bottom edges of the side plates are welded to the edges of the plate 14 to form a rigid structure. The kicker plate 15 makes up the back side of this portion of the bag receptacle. The upper portion of the bag receptacle is enclosed by the upper left side plate 16 and guide rods 17. These rods are held to the frame at their bottom ends by guide bar mount 18 and at their top ends by the presser cylinder mount 19. The upper and lower portions of the bag receptacle are covered by a door 20.

Referring to Figure 2 it will be seen that the door 20 is made up of a plate 20a and angle members 20b, which are screwed to the plate and serve to brace the door where it meets the bag receptacle and at the top and bottom edges. This door is screwed to a door hinge shaft 21 rotatably mounted in upper and lower angle supports 22 and 23 attached to the frame member 11. The door is provided with clips 24 which fit against the outside of plates 12 and 13 when the door is closed over the receptacle.

Passing through the vertical door angles 20b is a door lock shaft 25 (see Figure 4) which is held in place at the one end by a plate screwed into the shaft and at the other end by a door lock 26 pinned to the shaft. The door lock mechanism is shown more fully in Figure 7. The door lock is provided with a pin 27 projecting from each side of the door lock. One end of this pin cooperates with a recess 12b in a strip 12a affixed to the top edge of plate 12 and the other end has secured to it a spring 28, which is held to the door frame by pin 29. The spring holds the door lock down and the pin in the recess thus keeping the door locked against the front of the bag receptacle. When the door trip arm 30, mounted on the upper press plate 31, moves downwardly against the curved edge of the door lock, it presses the door lock outward and lifts the pin 27 from the recess in the plate 12, releasing the door and permitting it to swing open.

To make the door swing open when it is released, as described above, it is provided with a conventional door check 32 (see Figure 5) which pulls the door open approximately 120° and serves as a shock absorber to stop it at that position. The rod 33 from the door check is pivotally attached to a bracket 34 which is screwed to the door hinge shaft 21. A strap hinge 35 holds the

door check to the plate 13. It has been found that this door check can be dispensed with if the bag press is mounted in a position tilted at an angle approximately 17° to the left of vertical and 17° backward. This not only serves to prevent the stacked bags from falling out of the bag receptacle when the door is open, but also results in the door falling open by itself when the door trip arm strikes the door lock. In the latter case it is only necessary to provide a stop on the door hinge shaft to prevent the door from swinging open too far.

Figure 1 further shows an air cylinder 36 bolted to mounts 19 and 37, which are in turn screwed to the frame 11. The air cylinder shaft 38 has a top bumper plate 39, top bumper 40 and lower bumper 41. Attached to the lower end of the shaft 38 is the U-shaped upper press plate 31. This press plate is provided with two holes through which pass the guide rods 17, thus allowing the press plate to slide up and down on these rods. Affixed to the back end of the upper press plate 31 is an angle iron 42 which acts to release the valve safety trip, as will be more fully described hereinafter.

The assembly for ejecting the bags and wrapper from the bag receptacle is shown in Figures 3 and 4. The kicker plate 15 is bolted to the shaft 43 of an air cylinder 44 which is affixed to the frame 11. It will be noted that the upper edge of the kicker plate has two cut-out portions which permit the face of the plate to line up flush with the forward edges of the guide rods 17 (see Figure 5). A three sided pusher 45 for moving the wrapper off the bag receptacle at the same time the stacked bags are ejected is made up of angle irons 45a and 45b joined by a flat cross piece 45c secured to the angle irons. The upper ends of the angle irons are screwed to the top of the kicker plate 15 so that the kicker plate, moving inside the bag receptacle, and the pusher, moving outside the bag receptacle, operate as a single unit. To furnish rigidity to the pusher and insure simultaneous movement of the kicker plate and pusher, there are two guide shafts 46 affixed to each side of the pusher. These four guide shafts are bolted to a guide plate 47. In addition there are four bumper shafts 48 affixed to the kicker plate, two being above and two below the air cylinder 44. These four bumper shafts are likewise bolted to the guide plate 47. Threaded onto the shafts 48 are bumpers 49 which cushion the blow as the kicker plate assembly ejects the stacked bags. Figure 3 shows the points at which the guide and bumper shafts are affixed to the pusher and kicker plate. Referring to Figures 1 and 4, the guide and bumper shafts pass through and are supported by upper and lower plates 50 which are screwed to the frame 11. The guide plate 47 also has bolted to it a pair of compression springs 51 and 52, which actuate the pistons in a pair of valves 53 and 54. It will be seen that the assembly for ejecting the bags and wrapper from the bag receptacle is so constructed that the kicker plate, pusher, guide shafts, bumper shafts, guide plate and compression springs all cooperate to move as a unit.

The valves 53 and 54, screwed to a valve mount 55 which is in turn screwed to the frame 11, are conventional four way air valves, each having a hand lever attached by a clevis mount to the piston of the valve. The action of these valves will be described further in explaining the operation of the bag press. The piping which connects the valves and air cylinders is shown in Figure 1.

An air line 56 provided with a hand shut-off valve 57 is connected between the valves 53 and 54 and furnishes air pressure to each. A pipe 58 carries air from one side of the valve 53 to the top of the air cylinder 36 while another pipe 59 carries air from the other side of the same valve to the bottom of the air cylinder 36. Similarly pipes 60 and 61 carry air from the valve 54 to the air cylinder 44.

To prevent the operator from pulling the handle of valve 54, which would actuate the air cylinder 44 and the kicker plate 15 and eject the stacked bags, before such bags have been compressed by the upper press plate 31, a valve safety trip has been employed in connection with valve 54. This is shown in Figures 8 and 9 and consists of a plate 62, which is held to the valve mount 55 by shoulder screws 63 threaded into the mount, said screws being set in slots 64 which permit the plate 62 to move up and down along the mount. There is also a slot 65 for the guide shaft 46. The base of the mount 55 has a small projection which carries a pin 66. A similar pin 67 extends from the bottom of the plate 62. Between these pins is a spring 68, so that the plate is normally in the position shown by the solid lines of Figures 8 and 9. This plate has a shoulder 69 protruding from the edge of one side, which shoulder fits in behind the clevis mount 50 of the hand lever of valve 54 and prevents movement of the hand lever and piston when the plate 62 is in its normal position (see also Figure 4). When the stacked bags are compressed by the upper press plate 31, the angle iron 42 affixed to this press plate slides the plate 62 downward and moves the shoulder 69 out of the path of the clevis mount of the hand lever of valve 54, thus allowing the operator to move the said hand lever and actuate the valve. This is shown by the dotted outlines of angle iron 42 and plate 62 in Figure 9.

It will be observed in Figures 3 and 6 that there is a gap between the top of left side plate 13 and the bottom of upper left side plate 16. To close this gap and present a flat surface along the full inner face of the left side of the bag receptacle when the bags are being stacked, a trap door 70 has been attached by hinges 71 to the bottom of plate 16. Secured to the back outer face of this trap door is an angle iron 72 one piece of which projects from the door. Linked into a hole in this piece is one end of a spring 73, the other end of the spring being linked to a pin 74 secured in the side plate 13. Secured to the back inner face of this trap door is a triangular piece 75 which is back far enough to be out of the bag receptacle, but is in the path of the back end of the upper press plate 31 when it moves downwardly to compress the stacked bags. For a top view of this piece and its position see Figure 5. A stop lug 76, shown in Figure 1, is welded onto the bottom edge of the trap door. When the bags are being stacked in the bag receptacle the trap door 70, the angle iron 72 and triangular piece 75 are in the positions shown in Figure 3. After such bags have been compressed by the upper press plate 31, the trap door and its component parts are in the positions shown in Figure 6, thus insuring clearance around all sides of the lower bag receptacle for slipping the tube wrapper 77 over the receptacle.

The operation of the invention will be apparent from the foregoing description. Before the operator puts any bags in the bag receptacle, the door 20 is open, the upper press plate 31 is up, 75 the trap door 70 is closed flat, the kicker plate 15

is back, and the hand levers of the valves 53 and 54 are pushed back. When the required amount of bags have been stacked in the receptacle, it will be filled virtually up to the upper press plate 31. The operator then closes the door 20, which is locked in place by the door lock 26, and pulls forward the hand lever of valve 53. At this time the plate 62 of the valve safety trip is in its normal position and it is impossible for the operator to make a mistake and pull the hand lever of the other valve 54. Pulling forward the hand lever of valve 53 actuates the air cylinder 36 and moves the upper press plate downwardly to a predetermined position thus compressing the stacked bags within the lower portion of the bag receptacle. When the upper press plate descends to such position the door trip arm 30 strikes and releases the door lock 26 and opens the door 20, the triangular piece 75 moves the trap door 70 outwardly and out of the way, and the angle iron 42 slides the plate 62 of the valve safety trip downward and out of the path of the clevis mount of the hand lever of valve 54. At this point the bags are confined within the upper and lower press plates and the left and right side plates, so that the operator can slip a tube wrapper around such plates. After this has been done, the hand lever of valve 54 is pulled forward to actuate the air cylinder 44, which causes the kicker plate 15 and pusher to eject the stacked bags and wrapper simultaneously in the form of a neat and compact package. As the kicker plate reaches the end of its forward movement, the compression springs 51 and 52 mounted on the guide plate 41 strike the protruding ends of the pistons of the valves 53 and 54. This actuates the air cylinders 36 and 44 returning the upper press plate 31, the kicker plate 15 and the other cooperating parts to the positions they had when the cycle was started. The bag press is now ready to receive another stack of bags.

While I have illustrated one particular embodiment of my invention and one particular application thereof, it will be understood that various changes and modifications may be made therein and the invention may be very efficiently used in the packaging of other products which can be compressed and inserted in a wrapper. Furthermore, although the wrapper referred to herein is in the form of a tube, it will be understood that it may be in the form of a bag, carton or other similar receptacle which will satisfactorily fit on the press of the present invention and hold compressed products.

It will thus be seen that the objects herein set forth may readily and efficiently be attained and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A packaging press comprising a lower press plate on which paper bags may be stacked, an upper press plate for compressing the stacked bags, said plates and compressed bags being clear

on all four sides for substantially the full length of the bags to receive an encircling wrapper, a kicker plate and pusher for simultaneously ejecting the compressed bags and encircling wrapper from the press plates, means for actuating the upper press plate, and means for actuating the kicker plate and pusher.

2. A packaging press comprising a receptacle for paper bags in stacked relation, a hinged door adapted to strike and align the edges of the stacked bags and to cover the receptacle while the bags are being compressed, a press plate which compresses the stacked bags, said receptacle and plate compressing the bags being clear on all sides for substantially the full length of the bags to receive an encircling wrapper, a kicker plate and cooperating pusher for ejecting the compressed bags and encircling wrapper from the receptacle and press plate, means for actuating the upper press plate, and means for actuating the kicker plate and pusher.

3. A packaging press comprising a receptacle in which paper bags may be stacked, an upper press plate to compress the stacked bags, controllable means for actuating the press plate, said receptacle and plate while in compressed position being clear on all sides for substantially the full length of the bags to permit an encircling wrapper to be slipped around the receptacle, plate and compressed bags in a predetermined position relative to the length of the bags, a kicker plate and cooperating pusher which eject the compressed bags and encircling wrapper from the receptacle and press plate and retain the bags and wrapper in the said predetermined relative position during the ejection, and controllable means for actuating the kicker plate and pusher.

4. A packaging press comprising a receptacle in which paper bags may be stacked, a swinging door adapted to close against and align the edges of the stacked bags and to retain the bags within the receptacle while the bags are being compressed, a press plate to compress the stacked bags, means for actuating the press plate, means for swinging the door away from the receptacle after the bags have been compressed, said receptacle and plate while in compressed position being clear on all sides for substantially the full length of the bags to permit an encircling wrapper to be slipped around the receptacle, plate and compressed bags in a predetermined position relative to the length of the bags, a kicker plate and cooperating pusher which eject the compressed bags and encircling wrapper as a unit retaining the bags and wrapper in the said predetermined relative position during the ejection, and means for actuating the kicker plate and pusher.

WILLIAM L. DAVIS.
